(57) **CLAIM**

The ornamental design for a bicycle carrier, as shown and described.

DESCRIPTION

FIG. 1 is a rear, top, and right side perspective view of a bicycle carrier showing the new design;

FIG. 2 is a front, bottom, and left side perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The dashed lines and structures they depict form no part of the claimed design.
